UNITED STATES PATENT OFFICE.

WILLIAM R. FOX, OF GRAND RAPIDS, MICHIGAN.

TABULATOR FOR TYPE-WRITERS.

No. 839,129.

Specification of Letters Patent.

Patented Dec. 25, 1906.

Application filed September 16, 1904. Serial No. 224,764.

To all whom it may concern:

Be it known that I, WILLIAM R. FOX, a citizen of the United States, residing at the city of Grand Rapids, county of Kent, State of Michigan, have invented certain new and useful Improvements in Tabulators for Type-Writers, of which the following is a specification.

This invention relates to improvements in tabulators for type-writing machines.

It relates to the style of tabulator for which I applied for Letters Patent on May 6, 1904, Serial No. 206,684, and to certain improvements independent of those described or referred to in the said application. With the peculiar form of tabulator described in my former patent application a little care is required in the operation of the same, else if the carriage-stop happened to be over the notched tabulator-stop this tabulating might not be entirely accurate, and it was therefore necessary to take pains that the carriage be moved toward the starting-point a sufficient distance to insure that the carriage-stop be entirely beyond the notched tabulator-plate. This was never noticed in the ordinary operation of the machine; but when the machine was in the hands of beginners they might encounter difficulties of this kind.

The objects of this invention are, first, to provide an improved tabulator in which the defect above referred to is overcome; second, to provide an improved construction of the connections for the tabulator-stop; third, to provide an improved means of preventing the release of the carriage except when the tabulator is operated; fourth, to provide an improved means of releasing the escapement during the process of tabulating.

Further objects and objects relating to structural details will definitely appear from the detailed description to follow.

I accomplish the objects of my invention by the devices and means described in the following specification.

The invention is clearly defined, and pointed out in the claims.

A structure embodying the features of my invention is clearly illustrated in the accompanying drawings, forming a part of this specification, in which

Figure 1 is a detail side elevation view of the frame of a type-writing machine and a portion of its mechanism, the lower portion of the machine being in section, taken on a line corresponding to line 1 1 of Fig. 3. Fig.

2 is a detail rear elevation view of the parts of the machine appearing in Fig. 1 with a portion of the lower rear casing broken away to show the connection to the mechanism for releasing the escapement. Fig. 3 is a detail sectional plan view of the parts appearing in Fig. 1, taken on line corresponding to line 3 3 of Fig. 1. Fig. 4 is an enlarged detail elevation view of the escapement release structure, taken on a line corresponding to line 4 4 of Fig. 1 looking toward the right. Fig. 5 is a detail plan view of the parts illustrated in Fig. 4, taken on the same scale. Fig. 6 is a detail sectional view of the parts, taken on line 6 6 of Fig. 5 looking toward the left, the escapement-wheel tooth not appearing. Fig. 7 is a detail sectional view on line 7 7 of Fig. 3, showing one of the bars of the tabulator and its relation to the release-bar D. Fig. 8 is an enlarged detail sectional view taken on line 8 8 of Fig. 3, showing the tabulator release-bar D and its connection to the connecting-rod D'. Fig. 9 is a detail sectional view taken on line 9 9 of Fig. 3, showing the arrangement of the tabulator-bar and whereby it swings the tabulator locking mechanism out of engagement and permits the release-bar to release the carriage. Fig. 10 is a detail sectional view taken on line 10 10 of Fig. 3, showing the method by which the release-bar is locked, except when one of the tabulator-keys is pushed in. Fig. 11 is a vertical transverse detail sectional elevation view of the tabulating-key connections, taken on a line corresponding to line 11 11 of Figs. 1 and 3. Fig. 12 is an enlarged detail view of one of the adjustable stops U.

In the drawings, similar letters of reference refer to similar parts throughout the several views, and the sectional views are taken looking in the direction of the little arrows at the ends of the section-lines.

Referring to the lettered parts of the drawings, A is the main frame of a Fox type-writing machine, the top plate A' being in the usual form and bearing a carriage M on suitable ways N.

B is a removable toe-piece across the front of the machine, serving to support the front ends or buttons I' of the keys I of the tabulator mechanism and the connecting-rods D' for the release-bar D, which reciprocate through suitable bearings therein. A transverse bar B'' is supported by forwardly-extending arms B' B' from this removable toe-piece, and the tabulator-rods are arranged

through apertures in this bar and are adapted to reciprocate therethrough.

The connecting-rods D' for the release-bar D are supported at their rear ends by the bell-crank arms E', which are secured to the transverse rock-shaft E through the rear portion of the machine. The arms B' extend forwardly and upwardly beyond the cross-bar B'' and terminate in eyes b. The rod b' extends through these eyes, and a plate C is hinged thereto and rests upon the rods of the tabulator and upon the connecting-rods D' from the release-bar D. The front edge of this plate C is turned upwardly at an oblique angle c, where it rests upon the tabulator-keys I. Collars i' are on each of these keys I and are beveled toward their rear sides, so that they pass readily under the upturned edge c of the plate C and swing the same upwardly. Portions d' at each end of this swinging plate C rest upon the connecting-rods D' and are not turned up, but extend straight rearwardly. Square-shouldered collars d are on the connecting-rods D of the tabulator release-bar in position to engage these portions d', so that the release-bar cannot be pushed in unless a tabulator-plunger is pushed in in advance of it to such an extent as to raise the lock-plate C. This prevents any accidental release of the carriage until the tabulator-plunger is pushed in and makes it necessary that the tabulator-plunger be operated independently of the release-bar to the extent of properly insuring the co-action of the two parts. The square shoulders or collars d are concaved slightly at the center to securely embrace the rounded parts d'.

A rock-shaft E, as I have already stated, is through the rear part of the machine, and the connecting-rods D' connect the tabulator release-bar D to the downwardly-depend-ing arms E', secured to the rock-shaft. A laterally and rearwardly extending arm H is secured directly to the rock-shaft, and an upwardly-extending rod h is the connection from this rock-shaft to the release means for releasing the escapement of the carriage. The escapement is the wheel-escapement described in the application of W. R. Fox and Glenn J. Barrett, Serial No. 117,774, filed July 31, 1902.

A lever m is provided and fulcrumed on a pivot on the offset portion of the rock-shaft P, which carries the escapement mechanism, and the connecting-rod h is connected to the end of it. A beveled finger m' extends upwardly from the lever m into contact with the inner dog n, so that when the rod h is pulled down this beveled finger m' is thrown up between the dogs and the inner dog is crowded out of engagement with the escapement-wheel by the inclined finger m', (see Figs. 4, 5, and 6, the inclination fully appearing in Fig. 6,) and the carriage is released,

so that it can move into contact with any tabulator-stop that may be in position. A spring m'' withdraws the finger m' and holds it normally out of engagement with the dog. The rock-shaft P, with its offset portion, is pivoted on the pivots P' in the frame, and this rock-shaft is rocked by a connection to the universal bar X, consisting of a rod x, connecting to an arm on the rock-shaft, the arm being indicated by the dotted lines in Fig. 1.

On this machine the tabulator is divided into three sections having three independently-movable vertical notched bars g' g' g'', as appears in Figs. 2 and 3. The tabulator plungers and keys are divided into similar groups, each group of which is connected with its appropriate tabulator-stop at the rear. Beginning at the left, the first two keys connect to stop g'', the next four to stop g', and the right-hand four to stop g. By dividing the tabulator into groups in this way the keys of each group may have less movement than would be required where they are all connected to a single notched tabulator-bar, as in my prior application for patent, which is obviously of some advantage, and, again, as I have already remarked, there is no likelihood of the tabulator interfering with the stop on the carriage should it transpire that the carriage-stop was near the tabulator-stop at the time of the actuation of the tabulator.

A cross-bar J is put across the machine, and this carries suitable sleeves J' J'' J''', from which are suspended by suitable arms K bars K' K'' K''', arranged transverse to the machine in such a position as to be engaged and actuated by the plungers I of the tabulator, the bar K' being for the tabulator-plungers at the right of the machine, K'' for those at the middle, and K''' for those at the left as the operator sits facing the machine.

Arms k' k'' extend upwardly from the sleeves J' J'' J''', respectively, and connecting-rods L are secured to these upwardly-extending arms and extend rearwardly and connect them to arms F F' F'', respectively.

On the rock-shaft E toward the rear of the machine are a series of sleeves corresponding to the first, second, and third groups of keys, and these sleeves are provided with the upwardly-extending arms F F' F'' just referred to.

Rearwardly-extending arms f f' f'' are secured to each of the corresponding sleeves and are connected directly to the lower-ends of the vertically-movable tabulator-bars g' g'', respectively. (See Figs. 1 and 3.)

The tabulator-keys I are of graded lengths for each section, and the sections are so arranged that they operate on the depression of the different keys different amounts to raise the different tabulator stop-bars to the required height.

The tabulator-stops g g' g'' are arranged at the rear of the machine side by side in suitable guides (see Fig. 2) and are adapted to be raised separately by the mechanism heretofore indicated on the depression of the different appropriate tabulator-keys. The upper ends of these tabulator-bars have a notched construction step by step, like that in my former patent application herein referred to, the same being in all particulars the same, except that each stop is provided with fewer notches, which, as before remarked, avoids the necessity of raising the whole device and saves motion, and this also enables a finer gradation than is accomplished by the device of the former application, this device being an improvement upon that device in that particular.

The various parts I have referred to are provided with springs for returning them to their normal position. The springs e connect to the downwardly-projecting lever E' and return the tabulator release-bar to the normal position. Springs q (see Fig. 3) return the tabulator-stops and connections to their normal position. Springs i'' , resting against the collars i on the tabulator-keys, return them to their normal position after actuation.

The arrangement of the tabulator-keys and tabulator release-bar appears clearly in Fig. 7, the tabulator-key being movable independent of the bar, all of which is clearly pointed out and claimed in my former patent application, but which is a desirable feature in the present device.

A series of stops U are adjustable along the stop-bar S at the rear of the machine, against which the carriage moves when it is released after successive printing; but this feature is made the subject matter of an independent patent application, filed December 6, 1902, Serial No. 134,109, and therefore need not be extensively described herein.

The escapement mechanism for the carriage is here illustrated only sufficiently to show the operation of my improved tabulating device. It is made the subject-matter of a patent by myself and Glenn J. Barrett, No. 775,269, issued November 15, 1904, and is not sought to be claimed in this connection. So far as this device is concerned the release mechanism consists of a rocker-bar P , on which are supported a pair of dogs n n' on vertical pivots, adapted to move horizontally and engage successively the teeth of the escapement-wheel R . A pin l is between the dogs to properly locate the same, the dogs being held normally toward each other by the coiled spring l' . As it is not sought to claim this structure specifically, a more extended description is not given, because this invention is adapted to a great variety of typewriters with different escapement devices.

The rocker-bar P , carrying the escapement-

dogs, oscillates transversely to the escapement-wheel, the same being carried by pivots at each end.

Having thus described my invention, what I claim as new, and desire to secure by Letters Patent, is—

1. In a tabulator for type-writers, the combination with a carriage of an escapement mechanism therefor; a suitable stop, or stops, at the rear of the carriage; a series of vertically-movable tabulator-bars g g' g'' with graduated notches at their upper ends for engaging the stop or stops of the carriage; a rock-shaft E in the lower part of the machine with a series of rocking sleeves F F' F'' thereon corresponding to the series of tabulator-bars and provided with arms connecting thereto respectively; a series of corresponding groups of tabulator-keys I of different lengths held normally outward by suitable springs in the lower front part of said machine; a transverse rod J carrying sleeves J' J'' J''' beneath which are suspended by suitable arms the transverse bars K K' K'' positioned and adapted to be actuated by the said keys; upwardly-projecting arms k k' k'' on said sleeves with connections therefrom to arms on the corresponding sleeves F F' F'' whereby the respective tabulator-bars will be operated independently different distances according to the key depressed; a release mechanism for the carriage-escapement consisting of a lever m with a finger m' in position to withdraw the engaging dog and release the type-writer carriage; a spring m'' to hold said release mechanism normally disengaged; an arm H on the rock-shaft E and a connection h therefrom to the lever m ; downwardly-depending arms E' on the rock-shaft E ; a tabulator release-bar D below and in front of the machine, suitably perforated for the free passage of the tabulator-keys I ; connecting-rods D' from each end of this release-bar to the depending arms E' on the rock-shaft E ; a pivoted plate C hinged at b and resting upon the tops of the connecting-rods D' and the tabulator-keys I , having its central part turned up at c and having an end portion d' which is flat and resting close against the connecting-rods D' ; square-shouldered collars d d on the connecting-rods D' to contact with the portion d' to prevent the inward movement of the tabulator release-bar and lock the tabulator release mechanism; and beveled collars i' on the keys I , adapted to pass under the upturned edge portion of the main plate C to unlock the tabulator-release when a tabulator-key is depressed, all coacting substantially as described and for the purpose specified. 125
2. In a tabulator for type-writers, the combination with a carriage of an escapement mechanism therefor; a suitable stop or stops at the rear of the carriage; a series of vertically-movable tabulator-bars with graduated 130

notches at their upper ends for engaging the stop or stops of the carriage; a rock-shaft in the lower part of the machine with a series of rocking sleeves F, F', F'', thereon corresponding to the series of said tabulator-bars, and provided with arms connecting thereto respectively; a series of corresponding groups of tabulator-keys I of different lengths held normally outward by suitable springs in the lower front part of said machine; a transverse rod J carrying sleeves J' J'' J''' beneath which are suspended by suitable arms the transverse bars K K' K'' positioned and adapted to be actuated by the said keys; upwardly-projecting arms k k' k'' on said sleeves with connections therefrom to arms on the corresponding sleeves F F' F'' whereby the respective tabulator-bars will be operated independently different distances according to the key depressed; a release mechanism for the carriage-escapement; a tabulator release-bar D below and in front of the machine, suitably perforated for the free passage of the tabulator-keys I; connecting-rod D' from each end of this release-bar to the release mechanism; a pivoted plate C hinged at b and resting upon the tops of the connecting-rods D' and the tabulator-keys I, having its central part upturned at c and having an end portion d' which is flat and resting close against the connecting-rods D'; square-shouldered collars d on the connecting-rods D' to contact with the portion d' to prevent the inward movement of the tabulator release-bar and lock the tabulator release mechanism; and beveled collars i' on the keys I adapted to pass under the upturned edge portion of the main plate C to unlock the tabulator-release when a tabulator-key is depressed, all coacting substantially as described and for the purpose specified.

3. In a tabulator for type-writers, the combination with a carriage of an escapement mechanism therefor; a suitable stop, or stops, at the rear of the carriage; a series of vertically-movable tabulator-bars g g' g'' with graduated notches at their upper ends for engaging the stop or stops of the carriage; a series of groups of tabulator-keys I, a group for each tabulator-bar, the different keys of each group being of different lengths; suitable connections from said keys to their corresponding tabulator-bars; a release mechanism for the carriage-escapement, consisting of a lever m with a finger m' in position to withdraw the engaging dog and release the type-writer carriage; a spring m'' to hold said release mechanism normally disengaged; a rock-shaft E having an arm H and a connection h therefrom to the lever m; downwardly-depending arms E' on the rock-shaft E; a tabulator release-bar D below and in front of the machine, suitably perforated for the free passage of the tabulator-keys I; connecting-rods D' from each end of this release-bar to the depending arms E' on the rock-shaft E; a pivoted plate C hinged at b and resting upon the tops of the connecting-rods D' and the tabulator-keys I, having its central part upturned at c and having an end portion d' which is flat and resting close against the connecting-rods D'; square-shouldered collars d on the connecting-rods D' to contact with the portion d' to prevent the inward movement of the tabulator release-bar and lock the tabulator release mechanism; and beveled collars i' on the keys I adapted to pass under the upturned edge portion of the main plate C to unlock the tabulator-release when a tabulator-key is depressed, all coacting substantially as described and for the purpose specified.

wardly-projecting arms k k' k'' on said sleeves with connections therefrom to arms on the corresponding sleeves F F' F'' whereby the respective tabulator-bars will be operated independently different distances according to the key depressed; a release mechanism for the carriage-escapement; a tabulator release-bar D below and in front of the machine, suitably perforated for the free passage of the tabulator-keys I; connecting-rod D' from each end of this release-bar to the release mechanism; a pivoted plate C hinged at b and resting upon the tops of the connecting-rods D' and the tabulator-keys I, having its central part upturned at c and having an end portion d' which is flat and resting close against the connecting-rods D'; square-shouldered collars d on the connecting-rods D' to contact with the portion d' to prevent the inward movement of the tabulator release-bar and lock the tabulator release mechanism; and beveled collars i' on the keys I adapted to pass under the upturned edge portion of the main plate C to unlock the tabulator-release when a tabulator-key is depressed, all coacting substantially as described and for the purpose specified.

4. In a tabulator for type-writers, the combination with a carriage of an escapement mechanism therefor; a suitable stop, or stops, at the rear of the carriage; a series of vertically-movable tabulator-bars g g' g'' with graduated notches at their upper ends for engaging the stop or stops of the carriage; a series of groups of tabulator-keys I, a group for each tabulator-bar, the different keys of each group being of different lengths; suitable connections from said keys to their corresponding tabulator-bars; a release mechanism for the carriage-escapement, consisting of a lever m with a finger m' in position to withdraw the engaging dog and release the type-writer carriage; a spring m'' to hold said release mechanism normally disengaged; a rock-shaft E having an arm H and a connection h therefrom to the lever m; downwardly-depending arms E' on the rock-shaft E; a tabulator release-bar D below and in front of the machine, suitably perforated for the free passage of the tabulator-keys I; connecting-rods D' from each end of this release-bar to the depending arms E' on the rock-shaft E; a pivoted plate C hinged at b and resting upon the tops of the connecting-rods D' and the tabulator-keys I, having its central part upturned at c and having an end portion d' which is flat and resting close against the connecting-rods D'; square-shouldered collars d on the connecting-rods D' to contact with the portion d' to prevent the inward movement of the tabulator release-bar and lock the tabulator release mechanism; and beveled collars i' on the keys I adapted to pass under the upturned edge portion of the main plate C to unlock the tabulator-release when a tabulator-key is depressed, all coacting substantially as described and for the purpose specified.

edge portion of the main plate C to unlock the tabulator-release when a tabulator-key is depressed, all coacting substantially as described and for the purpose specified.

5. In a tabulator for type-writers, the combination with a carriage of an escapement mechanism therefor; a suitable stop or stops at the rear of the carriage; a series of vertically-movable tabulator-bars with graduated notches at their upper ends for engaging the stop or stops of the carriage; a series of groups of tabulator-keys I, a group for each tabulator-bar, the different keys of each group being of different lengths; suitable connections from said keys to their corresponding tabulator-bars; a release mechanism for the carriage-escapement; a spring m'' to hold said release mechanism normally disengaged; a rock-shaft E having an arm H and a connection h therefrom to the release mechanism; downwardly-depending arms E' on the rock-shaft E; a tabulator release-bar D below and in front of the machine, suitably perforated for the free passage of the tabulator-keys I; connecting-rods D' from each end of this release-bar to the depending arms E' on the rock-shaft E; a pivoted plate C hinged at b and resting upon the tops of the connecting-rods D' and the tabulator-keys I, having its central part upturned at c and having an end portion d' which is flat and resting close against the connecting-rods D'; square-shouldered collars d d on the connecting-rods D' to contact with the portion d' to prevent the inward movement of the tabulator release-bar and lock the tabulator release mechanism; and beveled collars i' on the keys I, adapted to pass under the upturned edge portion of the main plate C to unlock the tabulator-release when a tabulator-key is depressed, all coacting substantially as described and for the purpose specified.
6. In a tabulator for type-writers, the combination with a carriage of an escapement mechanism therefor; a suitable stop or stops at the rear of the carriage; a series of vertically-movable tabulator-bars with graduated notches at their upper ends for engaging the stop or stops of the carriage; a series of groups of tabulator-keys I, a group for each tabulator-bar, the different keys of each group being of different lengths; suitable connections from said keys to their corresponding tabulator-bars; a release mechanism for the carriage-escapement; a tabulator release-bar D below and in front of the machine, suitably perforated for the free passage of the tabulator-keys I; connecting-rods D' from each end of this release-bar to the release mechanism; a pivoted plate C hinged at b and resting upon the tops of the connecting-rods D' and the tabulator-keys I, having its central part turned up at c and having an end portion d' which is flat and resting close against the connecting-rods D';

square-shouldered collars d d on the connecting-rods D' to contact with the portion d' to prevent the inward movement of the tabulator release-bar and lock the tabulator release mechanism; and beveled collars i' on the keys I adapted to pass under the upturned edge portion of the main plate C to unlock the tabulator-release when a tabulator-key is depressed, all coacting substantially as described and for the purpose specified.

7. In a tabulating device for type-writers, the combination with the carriage of an escapement mechanism therefor of the wheel type; dogs on opposite sides of said wheel, one of which normally engages the same; a lever m with a finger m' projecting up between the dogs for withdrawing the dog to release the carriage; a spring for holding said lever normally in the inoperative position; a tabulator release-bar in front of the machine; connections therefrom to the said lever m; and tabulator devices with keys projecting through the said release-bar, the said keys and release-bar being movable independently, coacting for the purpose specified.

8. In a tabulator for type-writers, the combination with the carriage of an escapement mechanism therefor of the wheel type; dogs on opposite sides of said wheel, one of which normally engages the same; a lever m with a finger m' projecting up between the dogs for withdrawing the dog to release the carriage; a tabulator release-bar in front of the machine; connections therefrom to the said lever m; and tabulator devices with keys projecting through the said release-bar, the said keys and release-bar being movable independently, coacting for the purpose specified.

9. In a tabulating device for type-writers, the combination with the carriage of an escapement mechanism therefor of the wheel type; dogs on opposite sides of said wheel, one of which normally engages the same; a lever m with a finger m' projecting up between the dogs for withdrawing the dog to release the carriage; a tabulator release-bar in front of the machine; connections therefrom to the said lever m; and tabulator devices with keys in proximity to said release-bar, the said keys and release-bar being movable independently, coacting for the purpose specified.

10. In a tabulator for type-writers, the combination with the carriage of a suitable escapement mechanism therefor; a suitable stop, or stops, at the rear of the carriage; a tabulator-bar for engaging said stop; a plurality of horizontal tabulator-keys arranged under the front part of the machine and adapted to reciprocate back and forth; a tabulator release mechanism for the carriage; a tabulator release-bar below and in front of the machine; connecting-rods extending for-

wardly therefrom and connecting to the tab-
ulator-release; beveled collars on the tabu-
lator-keys; a square-shouldered collar on one
of the connecting-rods from the tabulator
5 release-bar; a hinged plate with a flat por-
tion resting on the tabulator-bar connection
to contact with the square-shouldered collar
and with a beveled portion resting on the
tabulator-keys, whereby, when a tabulator-
10 key is depressed, the release-bar is unlocked
and permitted to operate, coacting for the
purpose specified.

11. In a tabulator for type-writers, the
combination with the carriage of an escape-
15 ment mechanism therefor; a suitable stop, or

stops, at the rear of the carriage; a vertically-
movable tabulator-bar; a rock-shaft in the
lower part of the machine; horizontally-ar-
ranged keys in the lower front part of the ma-
chine; a bar in the rear of said keys supported
20 by and suspended from said rock-shaft; and
connections between the said rock-shaft and
tabulator-bar, coacting for the purpose speci-
fied.

In witness whereof I have hereunto set my 25
hand in the presence of two witnesses.

WILLIAM R. FOX.
